UNITED STATES PATENT OFFICE.

RICHARD TOEPLITZ, OF NEW YORK, N. Y., ASSIGNOR TO INTERNATIONAL TYPESETTING MACHINE COMPANY, OF NEW YORK, N. Y., A CORPORATION OF NEW YORK.

ASSEMBLING-ELEVATOR.

1,108,814.

Specification of Letters Patent.

Patented Aug. 25, 1914.

Application filed April 3, 1913. Serial No. 758,683.

To all whom it may concern:

Be it known that I, RICHARD TOEPLITZ, a citizen of the United States, residing at New York, in the county of New York and State 5 of New York, have invented new and useful Improvements in Assembling-Elevators, of which the following is a specification.

The present invention has reference to improvements in assembling elevators for line-type machines, and more particularly to the type of elevator which is adapted to receive matrices having two or more characters arranged at different heights thereon, whereby either upper or lower characters may be 15 brought into proper casting alignment at will.

It proposes, first, the provision of means whereby matrices which have been assembled at an upper level in the elevator are 20 prevented from falling to a lower level in case the supporting rail is moved away from the receiving end of the elevator, and, also, of means for effecting this movement of the rail automatically by the in-coming matrices as they are being assembled at a lower level; and, second, the provision of an improved method of mounting the aforesaid rail so as to guide its movement in a manner 25 advantageous to the assembling of matrices 30 at a lower level.

An embodiment of the invention is illustrated in the accompanying drawings, whereof:—

Figure 1 is a side elevation of the improved assembling elevator, with the rear part thereof removed; Fig. 2 is an elevation of the upper end portion of the elevator; Fig. 3 is a detail view of the gate and movable rail, the gate being shown in open position; Fig. 4 is a perspective view of the movable rail and its gate, the latter occupying its closed position; Fig. 5 is a compound view of the gate in side and end elevation; and Fig. 6 is a front elevation of the elevator in two different positions and with coöperating parts of the machine.

In most machines of this class in use at the present day, two-letter matrices are assembled in an elevator, known as the assembling elevator, at either or both of two different levels. The matrices are held at the lower level by one or two shelves or ledges whereon they rest, a similar shelf or rail being provided for holding the matrices at the

upper level. This upper rail is usually constructed in one or two pieces, and the whole rail, or part of it, is made movable at the receiving end, so as to provide an opening through which the matrices may pass down to the lower level. It so happens that when 55 matrices have been assembled upon the aforesaid rail, and it is then desired to assemble at a lower level, the act of providing such opening will cause the matrices already assembled at the upper level to drop down, 60 which necessitates their re-setting upon the rail by hand before the elevator is lifted to the transfer carriage, this being due to the fact that the opening must be large enough for the heaviest matrices to pass there- 65 through, and that two or more matrices are apt to be assembled at one time and, also, to enter the elevator by a combined downward and forward motion as they are acted on by the assembler before they have finished falling. These and other objections 70 are overcome in the present invention.

In the present instance, the matrices 1 are delivered by the chute 2 to the rotary assembler 3 which advances them to compose 80 a line in the assembling elevator 4. This elevator is shown as embodying opposed walls 5 and 6, as usual, the said walls being connected together toward their lower ends by the bolts 7 and being provided along their 85 inner sides with ribs 8 and 9, respectively, which ribs are arranged to coöperate with the ears 10 on the matrices, the latter, when assembling on the lower level, resting on these ribs and traveling longitudinally 90 thereon. Above the rib 9 is mounted the rail 11, which serves as a means for supporting the matrices at the higher level, being provided for that purpose with a rib 12. This rail is also provided with a depending 95 arm 13 that is pivoted at its lower end upon one of the bolts 7, the rail being adapted to rock thereon, so that the receiving end of its supporting rib may be brought either into or out of position to catch and retain 100 the in-coming matrices.

To control the entrance to the rail, or, in other words, the assembling of the matrices at the upper level, there is preferably provided a device which may be moved either 105 into or out of the path of the in-coming matrices, so as to close or open such entrance. This device, in the present construction, em-

2

bodies a movable gate 14 which is pivoted centrally upon a pin 15 secured to the receiving end of said rail, and is provided at its outer end with a finger-piece or handle 16 and at its inner end with a hook-shaped finger 17 that is curved upwardly and inwardly, as shown in Figs. 4 and 5. When the gate is lowered into the position represented in Figs. 1, 2, 4 and 6, its finger 17 rests upon the receiving end of the rail rib 12 and, hence, prevents the matrices from passing onto the rail, but when it is raised into the position depicted in Fig. 3, its finger lies at one side of said rib and the entrance to the rail is unobstructed. When said gate is in the latter position, it is advisable to hold it against accidental displacement, as hereinafter explained, and to effect this its finger-piece 16 is preferably engaged in a notch 18 formed in the front end of the elevator wall 5, but in such case the rail must first be moved to its extreme forward position at the receiving end of the elevator.

When it is desired to assemble matrices at the lower level, the gate is closed, and the in-coming matrices falling upon the curved surface of finger 17 and being forced forward by the assembler 3 will then push said gate and rail forwardly and upwardly, owing to the pivotal mounting of the latter. Any matrices which may have previously been assembled at the upper level, upon said rail, will be carried forward by the gate and thus prevented from falling off the rail. The rail is thus moved automatically by the in-coming matrices as far as may be necessary for them to properly assemble, which may depend upon the thickness of the matrices in use. It is to be noted that this movement of the rail away from the receiving end of the elevator not only provides space for the matrices to fall, but also provides ample room for them to be pushed forward while falling owing to the fact that the receiving end of the said rail travels in an upward path.

After a line of matrices has been assembled, the elevator is lifted in the usual manner, and as it moves upward the delivery end of the rail comes into contact with the inclined surface 19 of the delivery channel 20 which is a part of the frame of the machine. This inclined surface forces the rail back to its extreme position in the elevator, whereby the rail is caused to assume a horizontal position, as shown in dotted lines in Fig. 6. When the line has been transferred from the elevator, and the latter returned to assembling position, the operator may assemble matrices without touching the rail or gate, if it is desired to assemble at the same level as the last matrices in the preceding line. This is provided for by the automatic movement of the rail, which is effected by the in-coming matrices, as above de-

scribed. It will be apparent, therefore, that the operator may, at will, assemble matrices at either the lower level or the upper level, or he may assemble part of the matrices at the lower level and part at the upper level, or, if required, may assemble the successive matrices alternately at the two levels, without having to touch the matrices by hand.

Having described my invention, what I desire to claim is:

1. In a machine of the linotype class, an assembling elevator having a movable rail mounted therein for supporting matrices at an upper level; and a device carried by said rail for closing the entrance thereto, said device being adapted to be acted upon by the in-coming matrices to push the rail away from the elevator entrance, to allow matrices to pass to a lower level.

2. In a machine of the linotype class, an assembling elevator having a movable rail mounted therein for supporting matrices at an upper level; and a gate carried by said rail at its receiving end and adapted for movement into position to close the entrance to said end, said gate when in such position extending into the path of the in-coming matrices, whereby it will be engaged by the latter and pushed with said rail away from the elevator entrance, to allow matrices to pass to a lower level.

3. In a machine of the linotype class, the combination, with the assembling elevator; of a rail for supporting matrices at an upper level having a downwardly extending pivot arm pivotally mounted in said elevator at a point sufficiently below and forward of the receiving end of the latter to guide the receiving end of the rail in an upward and forward direction, thereby permitting said rail end to clear the in-coming matrices as the same are being assembled in a downward and forward direction at a lower level.

4. In a machine of the linotype class, the combination, with the assembling elevator; of a rail for supporting matrices at an upper level; means, controllable at will, to automatically move said rail in an endwise and upward direction away from the path of the in-coming matrices; and means actuated by the raising of the elevator to return the rail to normal position.

5. In a machine of the linotype class, the combination, with the assembling elevator; of a rail for supporting matrices at an upper level pivotally mounted in said elevator at a point sufficiently below and forward of the receiving end of the latter to guide the receiving end of the rail in an upward and forward direction, thereby permitting said rail end to clear the in-coming matrices as the same are being assembled in a downward and forward direction at a lower level; and a device carried by said rail for closing the

entrance thereto, said device being adapted to be acted upon by the in-coming matrices to effect the movement of the rail.

6. In a machine of the linotype class, the combination, with the assembling elevator; of a rail for supporting matrices at an upper level pivotally mounted in said elevator at a point sufficiently below and forward of the receiving end of the latter to guide the receiving end of the rail in an upward and forward direction, thereby permitting said rail end to clear the in-coming matrices as the same are being assembled in a downward and forward direction at a lower level; and 10 a gate carried by said rail at its receiving end and adapted for movement into position to close the entrance to said end, said gate when in such position extending into the path of the in-coming matrices, whereby it 15 will be engaged by said matrices and pushed with said rail away from the elevator entrance.

7. In a machine of the linotype class, the combination, with an assembling elevator 25 having a movable rail mounted therein for supporting matrices at an upper level; of a device carried by said rail for closing the entrance thereto, said device being adapted to be acted upon by the in-coming matrices to 30 push the rail away from the elevator entrance, to allow matrices to pass to a lower

level; and means actuated by the raising of the elevator to return said rail to normal position.

8. In a machine of the linotype class, the combination, with the assembling elevator; of a rail for supporting matrices at an upper level pivotally mounted in said elevator at a point sufficiently below and forward of the receiving end of the latter to guide the receiving end of the rail in an upward and forward direction, thereby permitting said rail end to clear the in-coming matrices as the same are being assembled in a downward and forward direction at a lower level; a 40 gate carried by said rail at its receiving end and adapted for movement into position to close the entrance to said end, said gate when in such position extending into the path of the in-coming matrices, whereby it will be 45 engaged by said matrices and pushed with said rail away from the elevator entrance; and means actuated by the raising of the elevator to return the rail to normal position.

In testimony whereof I have hereunto set 50 my hand in presence of two subscribing witnesses.
